EJECTING MECHANISM

Walter S. Sutowski, Garfield Heights, Ohio, assignor to Freeway Washer and Stamping Company, a corporation of Ohio

Application November 21, 1947, Serial No. 787,295

15 Claims. (Cl. 164—33)

1

My invention relates to ejecting apparatus for a press wherein stampings are ejected from a die assembly upon forming of the stamping by the punch of the press cooperating with the die assembly.

An object of my invention is to provide an ejecting mechanism operating in a manner to permit the speeding up of the operation of the punch press to a rate far exceeding the rate of operation heretofore obtainable.

Another object is the provision of an improved ejecting mechanism so adapted to the operating characteristics of a punch press that the efficiency and speed of the punch press may be greatly increased over that of punch presses without my ejecting mechanism.

Another object is the provision in an ejecting mechanism of a push-out device mounted in a "floating" condition and which is moved in one direction by the forward movement of the press punch and is moved in an opposite direction upon rearward movement of the press punch.

Another object is the provision in an ejector mechanism of a rigid and positive connection between the press punch and the push-out device for moving the push-out device away from the punch before the punch moves into the die opening.

Another object is the provision of a combination of levers and resilient means for operating a punch press ejector in a new and better manner to give heretofore unobtainable and unknown results in the operation of the press.

Another object is the provision of an ejector mechanism wherein the push-out device does not bear the strain or thrust of the forward movement of the plunger or ram and the plunger or ram does not meet any substantial resistance by the push-out device.

Another object is the provision for a novel combination in an ejector mechanism wherein the ejection of the stampings is properly timed or synchronized with the operation of the press plunger to obtain the greatest efficiency in ejection and in the operation of the press.

Another object is for actuating a push-out device by resilient means controlled, timed and energized by the driving means of the press.

Another object is the provision for the ejection of stampings by utilization of energy stored in resilient means, the energy being imparted to the resilient means by the forward movement of the press plunger, the transfer of energy from the press plunger to the resilient means being diverted from the die assembly and push-out de-

vice by provision of energy transfer means externally of the die assembly and push-out device.

Another object is the provision of a unique arrangement of pivoted levers and a resilient member for the operation of a push-out device in a die assembly.

Another object is the provision of an arrangement for proportioning the movement of a push-out device in an ejector mechanism to the movement of the reciprocating plunger of a press.

Other objects and a fuller understanding of my invention may be had by referring to the following description and claims, taken in conjunction with the accompanying drawings in which like character references indicate like parts, and in which:

Figure 1 is an end view of a punch press embodying my mechanism looking at the left-hand end of the press shown in Figure 2 in the direction of the arrows 1—1;

Figure 2 is a side view of a punch press embodying my invention and shows a portion of the press in section to illustrate the arrangement of the parts, the section being taken along the line 2—2 of Figure 1. The view of Figure 2 shows the reciprocating plunger of the press and the ejector mechanism in its withdrawn or rearward position;

Figure 3 is a view similar to that of Figure 2, but shows the press plunger and ejecting mechanism in the other of their extreme positions, that is, in the punching or forward position;

Figure 4 is an enlarged sectional view showing the detailed arrangement of the punch, die assembly and push-out device mounted on the press shown in Figures 1, 2, and 3;

Figure 5 shows a portion of the view shown in Figure 4 and illustrates the parts in a different operating position from that shown in Figure 4; and

Figure 6 is a view similar to that of Figure 5 and illustrates the parts in still another operating position. The views of Figures 4, 5 and 6 illustrate the various positions of the punch, die assembly, push-out device and means for operating the push-out device in various positions during the operating cycle of the press.

The press illustrated in the drawings is of the horizontal type, but it is understood that my invention is equally applicable to vertically disposed presses and other presses as well. For purposes of a reference in the description and claims, the left-hand end of the press shown in Figures 2 and 3 is the forward end, and movement toward this left-hand end is referred to as forward

movement and punching movement. The right-hand end of the press shown in Figures 2 and 3 is referred to as the rearward end; and movement of the parts toward this end is referred to as a rearward movement and withdrawing movement.

The press proper and without my ejecting mechanism is of the usual and standard type, except for such modifications as is necessary for the mounting and assembly of my ejecting mechanism and parts to the press. A frame 12 is carried by a base 11 in the usual manner. A flywheel 13 journaled on the frame 12 is driven by a motor 14 through a belt 15. By a usual cam and crankshaft arrangement, the flywheel 13 reciprocally drives a plunger or ram 16 on guideways carried by frame 12. A punch mounting arrangement assembly denoted generally by the reference character 17 is mounted on the end of the plunger 16, a suitable center post 24 of the assembly 17 being positioned in the head of the plunger 16. A punch 18 carried by the assembly 17 extends out and forwardly of the plunger 16 and is carried by the plunger 16 to reciprocate therewith.

A die-support portion 38 of the frame 12 is arranged transversely of the line of movement of the reciprocating plunger. The portion 38 of frame 12 carries a bolster plate 30 secured thereto. A die assembly denoted generally by the reference character 27 is carried by, and secured to, the bolster plate 30.

A pivot mounting or hinge 39 is secured to, and carried by, the portion 38 at the forward end of the press, that is, on the side of the portion 38 opposite of the die assembly. A lever arm 49 is pivotally carried by the pivot mounting 39. The lever arm 49 extends downwardly and approximately transversely of the line of movement of the reciprocating plunger. The arrangement of the lever arm 49 on the pivot mounting 39 is such that the lever arm swings on the pivot forwardly and rearwardly, that is, to the left and to the right in the views of Figures 2 and 3. The lower end of the lever arm 49, that is, at the end farthest removed from the pivot mounting 39, there is a niche or cutaway portion 52. A rod 51 disposed in a direction longitudinal of the press is disposed in this niche 52. One end of the rod 51 is carried by, and secured to, the press frame 12 by a suitable support bracket 50. The fit of the rod 51 in niche 52 provided in lever arm 49 is such that the lever arm 49 may freely swing back and forth relative to the fixed rod 51.

At the forward end of the rod 51, there is provided a resilient member consisting of a block of resilient rubber 53. This rubber block 53 is capable of compression to receive and store energy therein, and is capable of expansion to release the stored energy to adjacent parts. Washers or apertured plates 54 and 55 are mounted on rod 51 and disposed on opposite sides of the rubber block 53. The washer 55 has a loose fit on rod 51 so that the washer 55 may move along the rod 51 upon expansion and compression of the rubber block 53. A nut on the forward end of rod 51 secures the plate 54 to rod 51 and limits forward movement of block 53 so that forward movement of plate 55 on rod 51 causes compression of the rubber block 53.

Another lever arm 41 is pivotally carried by pivot mounting 42 secured to, and carried by, the frame 12 as indicated in the drawing. The disposition of the lever arm 41 and pivot mounting 42 is such that lever arm 41 may swing for-

wardly and rearwardly relative to the longitudinal dimension of the press. At the free or moving end of the lever arm 41, there is an elongated head 43 which is disposed in a recess 44 provided in the reciprocating plunger 16. Shock pads of rubber, fiber or other suitable material are provided on the ends of the head 43 as indicated in the drawings. A suitable open space is provided in the ribs and crosspieces of the frame 12 to permit the swinging of lever arm 41 between its two limits of movement. Another shock pad of rubber or fiber is provided on the side of the lever arm 41 to absorb shock in the lever swinging back to its rearward position and striking the stop provided by the web of the frame 12 as shown in the drawings. The disposition of the lever arm 41, pivot mounting 42 and elongated head 43 relative to the frame and to the reciprocating plunger is such that the lever arm 41 is swung forwardly and rearwardly on its pivot as the plunger is reciprocated. The arm 41 is swung forwardly upon forward movement of the reciprocating plunger, and rearwardly upon rearward movement of the plunger by the carrying of the head 43 in recess 44 of plunger 16.

Carried by, and secured to, the lever arm 41 intermediate its ends is a socket member 45. Socket member 45 may be secured to the arm 41 by welding it thereto or any other suitable means.

In the embodiment illustrated, the socket 45 is located about two-thirds of the length of arm 41 from the pivot mounting 42. As arm 41 swings back and forth, the socket 45 is carried therewith. The forward end of the socket member 45 has a recess or dwell, the sides of the recess being disposed to slant inwardly of the recess. A shock pad of rubber or fiber is disposed inwardly of the recess in socket member 45.

A rod 46 is disposed longitudinally of the press 40 and parallel to the line of movement of the reciprocating plunger. An opening 47 provided in a cross-web of frame 12 accommodates the rod 46 to permit the rod 46 to reciprocate through opening 47 in a slide fit. The rod 46 is so disposed as to float unconnected with other parts of the device and to be moved forwardly and backwardly between its two limits of movement, that is, between the positions shown in Figure 2 and Figure 3. An adjusting screw bolt 48 is threadably engaged in the arm 49. The inner or rearward end of the adjusting bolt 48 abuts against the forward end of rod 46, the rod 46 and adjusting bolt 48 being in alignment. The rod 46 is not connected to the bolt 48 and they engage each other by one being pushed against the other through external forces. A suitable lock nut on bolt 48 holds the bolt 48 in the position to which it has been adjusted. The adjusting bolt 48 reciprocates with the swinging of the arm 49.

Intermediate the ends of the arm 49 and nearest to the pivot 39 there is a spacer block 34 which is carried by, and secured to, the lever arm 49. The block 34 may be secured to the arm 49 by bolts, welding or other suitable means. The spacer block 34 swings with the arm 49 on the pivot mounting 39. A link member 33 is connected to the rear end of the block 34 in such a manner as to move with the block 34 and to reciprocate in the line of direction of the reciprocating plunger. A block 32 is connected to the rearward end of the link member 33 so as to move therewith. The connection of the link 33 to blocks 34 and 32 is such that as the lever arm 49 swings in an arc on the pivot mounting

39, the block 32 is moved back and forth in a straight line coinciding with the axis of the reciprocating plunger 16. A hardened steel plate 31 is secured to the rearward end of the block 32 by welding or other suitable means.

The block 32 and hardened plate 31 secured thereto extend through an opening 40 of a bolster plate 30, so as to reciprocate therein. Suitable bearing supports in portion 38 of the frame accommodate the block 32 to support and guide the same in its reciprocating motion. The link 33 provides a hinge whereby the swinging motion of block 34 is translated into reciprocating motion of block 32.

Bolted or otherwise secured to the bolster plate 30 is the die shoe 29. Bolted or otherwise secured to the die shoe 29 and bolster plate 30 is the die assembly 27. The die assembly 27 has an open space 28 provided therein.

The die assembly 27 is constructed in accordance with the shape of the stamping to be fabricated. In the illustration shown, the die assembly is formed for the stamping of metal washers, that is, discs with an opening through the center. To form the opening in the center of the washer, a piercer 37, of general cylindrical shape and solid throughout, is positioned in the die assembly centrally of the die opening. The piercer has its inner end abutting upon the die shoe 29.

The detailed arrangement of the punch assembly 17 is shown in Figure 4. A block 19 having the center post 24 is carried by, and secured to, the plunger 16. The block or punch holder 19 has a hard plate 20 attached thereto and a block or punch pad 21 secured to the hard plate 20. The punch proper 18 is secured in a suitable opening in the punch pad 21. The punch assembly consisting of punch holder 19, hard plate 20, punch pad 21, center post 24 and punch 18, comprises a unit which reciprocates with the plunger 16. To provide for accommodating slugs cut from the center opening of the washers by the piercer 37, a longitudinal opening 23 is provided in punch 18, and opening 23 registers with an opening 22 in the punch holder 19. The slugs are drawn off through the opening 23 and opening 22 by pneumatic means or other suitable means. As shown in the drawings, an appropriate strip of sheet metal 25 is moved along across the die assembly 27 by automatic or other means to consecutively bring unpunched sheet material over the die opening where a washer 56 is punched down into the die opening by the punch 18. The punch 18, in stamping out the washer 56 from the strip of sheet metal 25, pushes the washer 56 down into the die opening, as shown in Figure 4. Upon withdrawal or backward movement of the reciprocating punch 18, the sheet material 25 is moved along ready for the punching of another washer.

To remove the punched washer 56 or other stamping from the die assembly, the push-out ring 35 is positioned in the die opening and surrounding the piercer 37. The push-out ring 35 has a flange portion which is accommodated by the transverse opening 28, the accommodation of the flange of the push-out ring in the opening 28 being such that the push-out ring may move forwardly and backwardly in the die opening between limits. To press the push-out ring rearwardly, a plurality of push-out pins 36 extend through the die shoe 29 and into the lower part of the die assembly 27 to abut against the inner end of the push-out ring 35, that is, against the

flange of the push-out ring 35. The fit of the push-out pins 36 is a sliding engagement in the die shoe 29 and the base of the die assembly 27, so that the push-out pins 36 may freely reciprocate therein. It is preferred that there are three push-out pins 36 spaced equidistantly around the annular extent of the push-out ring 35, so that movement of all three pins 36 against the push-out ring 35 moves the push-out ring 35 in a straight line and without cocking in the die opening.

It is thus seen that upon movement of the push-out pins rearwardly toward the sheet material 25, the pins move the push-out ring rearwardly in the die assembly, and the push-out ring in turn ejects the formed washer 56 from the die opening. A transverse blast of air or other suitable means across the mouth of the die opening removes the ejected washer and carries it away from the die, or in the horizontally disposed press

illustrated gravity causes the formed washer to drop after ejection from the die opening by the push-out ring 35. It is also to be noted that upon forward movement of the punch into the opening of the die assembly during the stamping of a washer 56, the push-out ring 35 is moved forwardly away from the sheet material 25. This movement of the push-out ring 35 in turn pushes the three push-out pins 36 forwardly through their respective openings in the die and die shoe.

30 A stripper 26 may be positioned around the punch 18 to restrain the sheet metal 25 during the withdrawing or rearward movement of the punch in its stamping cycle.

The hard plate 31 mounted on the block 32 abuts against the forward end of the push-out pins 36, that is, at the end of the pins opposite from the push-out ring 35. Upon movement of the block 32 toward the sheet material 25, the push-out pins are moved by the hard plate 31 to move the push-out ring 35 rearwardly toward the sheet material 25, and thus eject the washer 56. Upon forward movement of the block 32 away from the sheet material 25, the hard plate 31 is moved away from the push-out ring 35. As the pins 36 and ring 35 may move freely or float, then the removal of the block 32 and plate 31 from the pins 36 and forward movement of the punch 18 against the washer 56 and ring 35 moves the ring 35 and pins 36 forwardly away from the sheet material 25. It is to be noted that the punch 18 only has to overcome the slight friction of the ring 35 and pins 36 to move them forwardly during the forward or punching operation of the punch upon withdrawal or forward movement of the block 32 and plate 31 away from the sheet material 25. In other words, there is substantially no resistance to the forward movement of the push-out device consisting of the push-out ring and push-out pins during the forward or stamping movement of the punch, as the ring and pins float and the backing of the plate 31 on the block 32 is removed to the position shown in Figure 4.

In operation of the press, the plunger 16 moves forwardly or to the left in the views of Figures 2 and 3, thus forcing the punch 18 through the sheet metal 25 to form the metal washer 56 in the die. At this point in the cycle, the parts are in the position shown in Figures 3 and 4. As the plunger or ram 16 moves forwardly, to the left of the views shown in Figures 2 and 3, lever arm 41 also moves forwardly or to the left, pivoting on pivot mounting 42. The arm 41 is moved by the engagement of the elongated head 43 by the wall of the recess 44 in the plunger 16. The

70 75 78

lever arm 41 carrying the socket 45 pushes rod 46 forwardly or to the left. The rod 46 pressing against the adjusting bolt 48 swings the lever arm 49 forwardly, to the left, as shown in Figures 2 and 3, on the pivot mounting 39. The movement and the timing of the arm 49 is adjusted by the adjusting bolt 48 so that movement of arm 49 may be made relative to the movement of the arm 41, and a greater or lesser amount of play may be provided between the ends of rod 46 and lever 41 at one end and bolt 48 at the other end. Forward movement of lever arm 49 presses against the plate 55 on rubber block 53 and compresses the rubber block 53 and thereby imparts energy thereto. Forward movement of lever arm 49 to the position shown in Figures 3 and 4 carries the block 32 and plate 31 thereon forwardly, that is to the left, by the link 33 and block 34, mechanically and positively pulling the plate 31 forwardly away from the sheet material 25 and removing all resistance to the push-out pins 36. This forward movement of the parts 31, 32, 33 and 34 by the leftward swing of lever arm 49, permits the push-out pins 36 and push-out ring 35 to move freely in the die assembly when the punch 18 is pushed into the die opening of die assembly 21.

When plunger 16 in its reciprocating cycle, moves back to the open position shown in Figure 2, the punch assembly 17 and punch 18 move with it. Lever arm 41 is moved rearwardly on its pivot mounting 42 upon this withdrawing or rearward movement of the plunger 16 to the position shown in Figure 2. Upon removal of the forward thrust on the rod 46 by the lever arm 41 and socket 45, the rubber block 53 is permitted to expand. The expansion of the rubber block releases the energy stored in it, and the plate 55 on block 53 forces the lever arm 49 to swing rearwardly, that is to the right as shown in Figure 2, to the position shown in Figure 2. This rearward movement of lever arm 49 causes the adjusting bolt 48 to move the rod 46 back to its position shown in Figure 2 where it is ready for another forward thrust by the socket 45 on lever arm 41.

The rearward swinging of the lever arm 49 by the force of the expanding rubber block 53 moves parts 34, 33, 32 and 31 rearwardly or to the right, and thus to the position shown in Figure 2 and in Figure 5. The energy in the rubber block thus forces the hard plate 31 against the end of the push-out pins 36, which in turn push the push-out ring 35 rearwardly in the die assembly toward the sheet material 25 and thereby eject the formed washer from the die assembly. The ejected washer or other stamping then falls clear of the press by gravity or may be removed by other means and the same cycle here described is repeated during the continuous reciprocation of the plunger 16.

In Figure 5 the washer has been ejected and the sheet material moved ready for the stamping of another washer. At this moment the push-out ring 35 and push-out pins 36 are in the position where they were left by the last rearward action of the hard plate 31, that is, the push-out ring 35 is next adjacent to the sheet material 25. The washer or other stamping has just been ejected and the sheet material 25 has moved along transversely of the die ready for another stamping operation. In this particular movement, the hard plate 31 is against the push-out pins 36 and is ready to withdraw from the push-out pins before the punch 18 reaches the sheet material to stamp out a washer.

In Figure 6, it is shown that as the punch 18 reaches the sheet material 25 and before the punch enters the die opening, the hard plate 31 carried by member 32 has anticipated this move and moved forwardly, that is, away from the sheet material 25. Thus, as the punch 18 commences to meet the resistance of the sheet material in the stamping operation, all resistance to the push-out ring and push-out pins is eliminated by the movement of the hard plate 31 and member 32 to the position of Figure 6, which is also the position of Figure 3, wherein the lever arm 49 has swung forwardly or to the left in Figure 3. The arrangement of the levers on their pivots, the spacing of the rod 46 from the pivots of the levers, and the spacing of the block 34 on the lever arm 49 from its pivot is such that the force of the block 32 and plate 31 is always withdrawn before the punch enters the punch assembly and there is substantially no resistance offered to the punch by the push-out device. The same arrangement is such that there is a proper and proportionate movement of the push-out device to eject the formed washers immediately after the withdrawal of the punch 18 from the opening of the die assembly. The arrangement provides for the timing of the ejection so that the washer is ejected immediately following the withdrawal of the punch and before the punch reaches its farthest limit before coming forward again. Thus, the way is clear and the washer is completely out of the way long before the punch starts forward on its next punching operation. The arrangement provides for this very fast ejection immediately following the withdrawal of the punch from the die and permits the press to be greatly speeded up over that possible with all other arrangements. Also, with the present arrangement here described, the ejected washer is not carried out of the die assembly with the punch and at the same rate, the lever and resilient system provided here making for a slight lag in time between the withdrawal of the punch from the die and the ejecting movement of the push-out device. This slight lag permits the washer to be ejected and moved sideward by gravity or other means in a manner possible and much faster than obtainable when a washer is moved out bodily with the punch and in constant engagement with the end of the punch during the withdrawal movement of the punch. The leverage system and the resilient means permits for the ejection of the stamped washers at just such a proper time during the stamping operations of the press that presses equipped with my device are able to operate much faster and more efficiently than by that obtainable with other ejecting systems. While the illustration in the drawings shows the stamping of a washer, it is of course understood that the same apparatus applies to other stampings which are to be ejected from the opening of a die. Variations in the lever arrangement are of course possible and the disposition and kind of the resilient means may be modified, all as will be suggested from the disclosure here made. These variations and modifications embody the inventive concept here disclosed within the scope of my invention as defined by the terms of the patent claims.

Although my invention has been described in its preferred form with a certain degree of particularity, it is understood that the present disclosure of the preferred form has been made only by way of example and that numerous changes in the details of construction and the combination

and arrangement of parts may be resorted to without departing from the spirit and the scope of the invention as hereinafter claimed.

What is claimed is:

1. In a punch press having a frame, a reciprocal ram, a die assembly carried by the frame, and a push-out device for ejecting stampings from said die assembly, said push-out device being movable forward into the die assembly upon forward stamping movement of said ram, apparatus for operating said push-out device comprising in combination a first lever pivotally carried by said frame and being engageable by said ram to be moved thereby upon forward stamping movement of said ram, a second lever pivotally carried by said frame, an engaging member carried by said second lever and movable therewith, said engaging member being positioned to engage and move said push-out device upon rearward movement of said second lever, a motion-transmitting member arranged to transmit motion from said first lever to said second lever upon forward movement of said ram, and a resilient member anchored to said frame and operatively engaging said second lever at a position along said second lever spaced from the fulcrum thereof and from said engaging member to provide for fractional movement of the engaging member relative to movement of the lever at said position, said resilient member being arranged relative to said second lever and directed to absorb energy upon forward movement of said ram and by said energy to move said second lever at said engaging member rearwardly upon rearward movement of said ram, the arrangement of said first lever, motion-transmitting member, second lever, resilient member and engaging member being such that upon forward movement of the ram the engaging member is moved forwardly away from said push-out device and energy is absorbed by said resilient member and upon rearward movement of the ram the engaging member is moved rearwardly against said push-out device to move the same for ejection of a stamping from said die assembly.

2. A mechanism for operating a push-out device for ejecting stampings from the die mounted on a punch press, said press having a ram and a frame, said ram being reciprocal to advance toward, and to withdraw from, said die and said push-out device being reciprocal to retract, and to extend, relative to said die, said mechanism comprising in combination, resilient means adapted to receive and release energy, first operating means operatively connected to said ram and said resilient means for recurrently imparting energy to said resilient means upon advancing movement of said ram toward said die and recurrently releasing energy from said resilient means upon withdrawing motion from said die, and second operating means connecting said resilient means and said push-out device to recurrently extend said push-out device upon the release of energy by said resilient means, said operating means including motion-dividing means to provide for an extending movement of said push-out device less than, and at a rate proportionate to, the withdrawing movement of said ram.

3. In a press having a frame, a reciprocal plunger carried by said frame, a driving member mounted on said frame for reciprocating said plunger, a die support carried by said frame, and a reciprocal push-out device carried by said die support for successively pushing stampings out of a die carried by said die support, said plunger

being movable in a first direction toward said die support and said push-out device being movable in an opposite direction, a mechanism for operating said push-out device comprising in combination a lever pivotally mounted to said frame, engaging means carried by said lever at a first distance from the lever pivot, said engaging means being positioned to engage said push-out device and to move the same in said opposite direction upon movement of said lever in said opposite direction, power-take-off means driven by said driving member, said power-take-off means operatively engaging said lever at a distance from said lever pivot and adapted to move said lever in said first direction upon movement of said driving member in said first direction, and power-reservoir means operatively connected to said lever at a distance from said lever pivot and from said engaging means and arranged relative to said lever so as to receive energy upon movement of said lever in said first direction by said power-take-off means and by said energy to move said lever in said opposite direction independently of, and unopposed by, the forwardly directed force of said power-take-off means, the said distances from the lever pivot being proportioned to provide for a movement of the engaging means by the lever in said opposite direction slower than, and at a rate proportionate to, the movement of the driving member in said opposite direction.

4. In an ejecting mechanism for a punch press having a frame, a reciprocal plunger and a push-out device for successively pushing out stampings from the die upon withdrawing motion of the plunger, comprising in combination a movable member, pivot means carried by said frame and pivotally supporting said movable member, engaging means connected to said movable member at a distance from said pivot means and adapted to engage said push-out device, operating means synchronized to move in unison with said ram, said operating means being arranged to operatively engage said movable member at a distance from said engaging means to move the movable member forwardly upon forward movement of said ram, and resilient means carried by said frame and operatively engaging said movable member at a distance from said engaging means, said resilient means being directed to move said movable member rearwardly upon rearward motion of said operating means, the spacing of said engaging means, operating means and said resilient means along said movable member from said pivot means providing for a relatively lesser movement of said push-out device by said engaging means in respect to the movements of said operating means and resilient means.

5. A mechanism for ejection of stampings from the die of a press, said press having a frame and a plunger sequentially movable forwardly toward said die and movable rearwardly from said die, said press also having a reciprocal push-out device for pushing stampings out of said die upon rearward motion of said plunger, said ram and die being disposed on a reference line coinciding with the path of, and the axis of, movement of said plunger, comprising in combination a lever, pivot means carried by said frame and pivotally mounting said lever at a lateral distance from said reference line to provide for forward and rearward movement of said lever, engaging means carried by said lever at a distance from said pivot means and positioned to operatively engage said push-out device adjacent said reference line upon rearward movement of said

lever to operate said push-out device and to disengage said push-out device upon forward movement of said lever, operating means carried by said frame and operatively connected to said plunger to move forwardly upon forward movement of said plunger, said operating means being positioned to operatively engage said lever at a lateral distance from said reference line and from said pivot means to move said lever at said reference line forwardly upon forward movement of said ram, and resilient means carried by said frame and operatively engaging said lever at a lateral distance from said reference line and from said pivot means and directed to move said lever at said reference line rearwardly upon termination of said forward motion of said operating means, the rearward movement of said lever by said resilient means being independent of, and unopposed by, the forward movement of said lever by said operating means, the disposition of said operating means and resilient means relative to said pivot means and the proportion of the lateral spacing of said pivot means, operating means and resilient means, respectively, from said reference line producing a rearward movement of the engaging means at said reference line which is slower in rate and less in distance than the rearward movement of said plunger at said reference line.

6. In a press having a frame, a reciprocable plunger carried by the frame, a driving member synchronized to operate in unison with the reciprocations of said plunger, a die support for carrying a die, and a reciprocable ejector by the die support for ejecting stampings from said die, a mechanism comprising in combination engaging means positioned in the line of movement of said ejector and movable to engage and move said ejector in a first direction to engage and move said ejector toward said plunger, lever means operatively engaging said driving member and said engaging means and arranged to move said engaging means in a second direction away from said plunger to permit said ejector to freely move away from said plunger upon forward stamping movement of the plunger, and resilient means operatively engaging said lever means at a point laterally distant from said engaging means, said resilient means being arranged and directed to be moved by said lever means upon movement of said driving member in said second direction and to move said lever means upon movement of said driving member in said first direction, the movement of said lever means by said resilient means moving said engaging means in said first direction in a motion proportioned to, and less than, the motion of said lever means at said point.

7. In a press having a frame, a ram plunger reciprocable longitudinally of said press and carried by the frame, a die support carried by the frame, and a push-out device carried by the die support for pushing stampings from the die, comprising in combination a first lever having one end pivotally carried by said frame and having a second end operatively engaged by said plunger to reciprocate upon reciprocation of said plunger, a second lever having one end pivotally carried by said frame and having a second end movable longitudinally of said press, a reciprocable rod disposed longitudinally of the press and having a first end operatively engageable by said first lever to be moved forwardly by said first lever upon forward movement of said plunger and having a second end operatively engageable by said second lever to move said second lever forwardly upon

forward movement of said rod and to be moved rearwardly by said second lever upon rearward movement of said second lever, the arrangement of the rod and levers being such that force is transmitted in a forward direction only through said rod from said first lever to said second lever upon forward movement of said plunger, an engaging member carried by said second lever at a first distance from the pivot of said second lever and positioned between said second lever and said push-out device, and a resilient member operatively engaging said second lever at a second distance from the pivot of said second lever and arranged and directed to be energized upon forward movement of said second lever and by said energy to move said second lever rearwardly upon rearward movement of said first lever, said second distance being greater than said first distance, the forward movement of said second lever withdrawing the engaging member from said push-out device and the rearward movement of said second lever moving the engaging member against the push-out device to move the push-out device rearwardly, the rearward movement of said push-out device to push out said stampings lagging the rearward movement of said second lever at said resilient member.

8. In a press having a frame, a reciprocal ram plunger, a punch carried by the plunger, and a die assembly having an open space therein, the combination of a push-out device positioned in said open space and freely reciprocal therein from ejecting position to stamping position, said push-out device being movable to said stamping position by said punch entering said die assembly, first means carried by the press and positioned to engage said push-out device, second means carried by the press and positioned to move said first means away from said push-out device, third means carried by the press and operatively movable in synchrony with said plunger to move said second means forwardly upon stamping movement of said plunger, and fourth means engaging said second means, said fourth means including resilient means arranged in relation to said second means for absorbing energy upon movement of said second and third means during stamping movement of said plunger and imparting energy to said second means to move the same upon withdrawing movement of said plunger, said second means including lever means for making the movement of said first means proportionately less than the stamping and withdrawing movements of said plunger, the arrangement of said first, second, third and fourth means providing for the withdrawing of said first means from the push-out device upon stamping movement of said plunger to remove resistance to the movement of the push-out device to said stamping position and for the engagement of said push-out device and movement of the same to ejecting position by said first means upon withdrawing movement of said plunger, the movement of said first means to engage and move said push-out device to ejecting position lagging the withdrawing movement of said plunger.

9. In a press having a frame, a reciprocable ram plunger, a punch carried by the plunger, a die assembly carried by the frame, said punch and die assembly forming a stamping upon entrance of said punch into the die assembly by stamping movement of said plunger, and a reciprocal push-out device carried by the die assembly for ejection of the formed stamping upon withdrawal of said punch from the die assembly.

bly by said plunger, mechanism for operating said push-out device comprising in combination engaging means adapted to engage said push-out device and move the same for the ejection of said stamping, positive means driven by said plunger for positively moving said engaging means forwardly away from said punch upon forward stamping movement of said plunger to substantially remove resistance to movement of said push-out device by said punch, resilient means for resiliently moving said engaging means into engagement with said push-out device to move said push-out device to ejecting position, said positive means and resilient means being connected to provide energizing of said resilient means by said positive means during stamping movement of said plunger and for movement of the engaging means by the energized resilient means upon withdrawing movement of said plunger, and means operatively interconnecting said engaging means and said resilient means for reducing the movement of said engaging means relative to the movements of said plunger, to provide for a movement of the push-out device in ejecting formed stampings that is less than the withdrawing movement of the punch from said die assembly.

10. In a press having a frame, a reciprocable ram plunger, a punch carried by the plunger, a die assembly carried by the frame and cooperable with said punch to form a stamping, and a push-out device carried by, and reciprocable relative to, said die assembly for ejecting the formed stamping, the combination of a backing member positioned adjacent said push-out device and adapted to engage and move said push-out device to ejecting position upon rearward movement of said backing member toward said plunger, a lever system connecting said plunger and said backing member, said lever system providing for forward movement of said backing member upon forward movement of said plunger, a resilient member connected to said lever system, said resilient member being arranged to be energized by said lever system upon forward movement of said plunger and being adapted to move said backing member, through said lever system, rearwardly upon rearward movement of said plunger, the ratio of the movement of said backing member to the movement of said plunger being determined by said lever system, said lever system being arranged to provide a movement of said backing member less than the movement of said plunger, the rearward movement of said backing member moving the push-out device for ejection of the formed stamping and the forward movement of said backing member removing resistance to the forward movement of said push-out device upon entering of the said punch in said die assembly.

11. In a press having a frame, a reciprocable plunger, a punch carried by the plunger, and a die, the combination of a freely reciprocable push-out device carried by the die, an engaging member in alignment with, and positioned forwardly of, said push-out device, said engaging member being adapted to move against said push-out device and to move it rearwardly upon rearward movement of said engaging member, a positive means for moving the engaging member forwardly upon forward movement of the plunger, impositive means for moving the engaging device rearwardly upon rearward movement of the plunger, said impositive means being positioned to be energized by said positive means, said posi-

tive and impositive means being arranged to move in paths parallel to, at a distance from, the line of movement of said plunger to provide for the removal of resistance to said punch in the die by said engaging member upon forward movement of the plunger, and lever means interposed between said engaging member and said positive and impositive means to provide for a degree of movement of said engaging member different from the degree of movement of said plunger, the differential of said movements being such that the ejecting movement of the push-out device is less than the withdrawing movement of the punch.

12. In a press having a frame, a reciprocable ram plunger, a punch carried by the plunger, a die, and a reciprocable push-out device associated with the die, the combination of an engaging member aligned with the push-out device to engage the same and move it to ejecting position after withdrawal of the punch from the die and to disengage the push-out device and to move away from the same upon entrance of the punch into the die, a lever pivotally carried by the frame and carrying said engaging member, biasing means arranged for biasing said lever toward the push-out device to move the engaging member into engagement with the push-out device and to move the same toward ejecting position, and operating means driven by the plunger during forward travel of the plunger and arranged for recurrently overcoming the bias of said biasing means upon forward movement of said plunger, the spacing of said biasing means and operating means along said lever relative to its fulcrum and said engaging member providing for a movement of said engaging member less than the movement less than the movement of said biasing means and operating means.

13. In a press having a frame, a reciprocable plunger, a punch carried by the plunger, and a die, the combination of a freely reciprocable push-out device carried by the die, an engaging member in alignment with, and positioned forwardly of, said push-out device, said engaging member being adapted to move against said push-out device and to move it rearwardly upon rearward movement of said engaging member, positive means driven in synchrony with the plunger for moving the engaging member forwardly upon forward movement of the plunger, and resilient means arranged for moving said engaging member rearwardly upon rearward movement of the plunger, said positive means and said resilient means being arranged in opposition to each other to provide energization of said resilient means by said positive means, said positive means and resilient means including lever means arranged to provide for movement of said engaging member less than the movement of said plunger whereby the ejecting motion of the push-out device is less than the withdrawing motion of the punch from the die, said positive means being arranged outwardly of the said die to provide for movement of said engaging member independently of the line of force from said punch through said die whereby resistance to said punch in said die by said engaging member is minimized.

14. In a press having a frame, a reciprocable plunger, a reciprocable push-out device carried by the frame for ejecting stampings, the combination of an engaging member adapted to engage said push-out device and to move said push-out device in one direction, positive means arranged to be driven by said plunger for moving

said engaging member in an opposite direction upon forward movement of said plunger, resilient means arranged for moving said engaging member in said one direction upon rearward movement of said plunger, said positive means and said resilient means being arranged in opposition to each other to provide energization of said resilient means by said positive means, and motion-dividing means operatively connecting said engaging member and said resilient means and arranged to provide for movement of the engaging member by the resilient means less than the movement of the resilient means in reaction to said positive means, the line of force through said positive means from said plunger to said engaging member being displaced from the line of force of said plunger.

15. A mechanism for operating a push-out device for ejecting stampings from the die mounted on a punch press, said press having a ram and a frame, said ram being reciprocal to advance toward, and to withdraw from, said die and said push-out device being reciprocal to retract and to extend relative to said die, said mechanism comprising, in combination, resilient means carried by said press, first operating means operatively connected to said ram and to said resilient means and arranged for energizing said resilient

5
10

means upon advancing movement of said ram toward said die and providing resilient resistance to said advancing movement of said ram by said resilient means, and second operating means operatively connecting said resilient means and said push-out device and arranged to recurrently extend said push-out device upon release of said energy by said resilient means, said operating means including proportioning means for proportioning the movement of said push-out device relative to, and less than, the movement of said ram.
